BOTTLE CAPPING MACHINE

George E. West, San Antonio, Tex.

Application August 13, 1938, Serial No. 224,775

8 Claims. (Cl. 226—85)

The device forming the subject matter of this application is a means for applying a cap to a bottle. The invention aims to improve the construction of the diaphragm whereby the cap is engaged upon and about the neck of a bottle or other receptacle. The invention aims, further, to provide novel means for controlling the flow of fluid pressure, preferably, air to and from the diaphragm, to provide novel means for venting the diaphragm with respect to the cushion which it engages, to provide novel means whereby a strip of cap material may be bent into operative relation to a cutting instrumentality, to provide a novel means for exhausting air from the cap applying device, to provide novel operative connections between the instrumentalities above specified and others to be alluded to hereinafter, and, generally, to improve and to enhance the utility of, devices of that type which 20 the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in elevation, a machine constructed in accordance with the invention;

Fig. 2 is a side elevation;

Fig. 3 is a sectional elevation showing certain of the valve mechanisms and attendant parts;

Fig. 4 is a horizontal section showing the lower arm of the support and parts associated with it;

Fig. 5 is a vertical sectional view showing the operative connection between the cutting means and the means for raising the receptacle to be capped;

Fig. 6 is a vertical sectional view illustrating the capping mechanism and the means whereby the bottle cap is cut from a strip;

Fig. 7 is a sectional view of the head and attendant parts;

Fig. 8 is a sectional view of the clutch;

Fig. 9 is a horizontal section showing the arm 50 of the support and attendant parts.

In carrying out the invention, there is provided a support 1, seen best in Fig. 2. The support 1 includes a base 2 of any desired construction, carrying a fixed vertical tubular post 3. A sleeve 4 is vertically adjustable on the post 3, and is

held in adjusted positions by a set screw 5. The adjustment afforded by the set screw 5 is for the mere purpose of locating the entire working mechanism at any desired height, and with that observation, the set screw 5 and the vertical adjustability of the sleeve 4 may be dismissed from further consideration.

The sleeve 4 carries a fixed upper horizontal arm 6 and a fixed horizontal lower arm 7. A casing 8 (shown in Figs. 4, 2 and 1) is secured to the outer end of the lower horizontal arm 7. The casing 8 carries, upon one side, a depending bearing bracket 9, seen in Fig. 1. A horizontal shaft 10 (Figs. 4 and 2) is journaled in the casing 8 and in the bracket 9. To one end of the shaft 10, an operating member 11, preferably a handle under the control of an operator, is secured.

A pinion 12 is fastened to the horizontal shaft 10, within the casing 8, and meshes with a rack bar 14 (Figs. 2 and 4) mounted to reciprocate vertically in the outer end of the lower arm 7. Figure 2 shows that a horizontal, bottle-supporting table 15 is secured to the upper end of the rack bar 14. Fixed uprights 16 are carried by the inner portion of the table 15. The bottle stands on the table 15 and is supported laterally by the uprights 16. The bottle is not shown in the drawings. The bottle may be a milk bottle, or any other receptacle capable of being capped in the machine forming the subject matter of this application. The word "bottle" is to be construed as meaning any sort of a receptacle which the machine can handle.

A vertically elongated, cylindrical, fluid pressure head 17 is carried by the outer end of the upper arm 6 of the support 1, and is shown in Figs. 2 and 6, for instance. The head 17 is surrounded by a detachable cap 18.

The lower end of the head 17 is surrounded by a cup-shaped resilient member 60, preferably made of rubber, and held on the lower end of the head 17 by a clamp ring 61. The cup-shaped resilient member 60 includes a diaphragm 62, provided at its center with a depending boss 63, as shown in Fig. 6. The side wall of the cup-shaped member 60 is supplied, close to the diaphragm 62, with an inwardly projecting annular rib 64. A vent conduit 19 is connected to the cap 18, and is sustained by a bracket 20 (Fig. 2) mounted on the upper arm 6 of the support 1. The cap 18 (Fig. 6) carries a depending sleeve 21, within which is located an abutment cushion 22, preferably made of rubber, the cushion having a bore 23 in communication with the vent 55

conduit 19. The cushion 22 preferably is secured to the cap 18, as shown at 24 in Fig. 6. There is an air space 25 in the head 17, about the sleeve 21. The air in the air space 25 is heated by any suitable means shown at 26. The source of air supply for the air space 25 preferably is a pipe 27 (Figs. 2 and 3) connected to the upper arm 6 of the support 1 at the top thereof. On the lower end of the pipe 27 there is a valve seat 28 (Fig. 3), adapted to cooperate with a valve 29 closed by a spring 30. The valve 29 is carried by a stem 31, slideable in a guide 32 mounted in the lower part of the arm 6, the stem extending downwardly below the said arm, as shown in Fig. 3. Between the guide 32 and the valve seat 28 there is a space 33 in the upper arm 6, and from the said space 33, a duct 34 (Figs. 3 and 9) leads to the air space 25 within the head 17. As shown in Fig. 9, a duct 44 is branched off from the duct 34 in the arm 6, and leads to a pipe 45, mounted on the arm 6, and carrying a gauge 46, whereby the pressure in the duct or conduit 34 can be read off. Air leaves the air space 25 of the head 17 through a duct 35, shown in Fig. 9, and this duct leads to a pipe 36 which, as shown in Fig. 3, is joined to a valve casing 37 having a valve seat 38. The valve casing 37 has an outlet 39, the seat 38 being located between the inlet 36 for the casing 37, and the outlet 39 therefor. A valve 40 cooperates with the seat 38 and is carried by a stem 41, a spring 42 cooperating with the stem and with a portion of the casing 37, to close the valve 40. In the stem 41 is interposed a connection 43 whereby the length of the stem may be adjusted.

The lower end of the valve stem 41 (Fig. 4) is pivoted somewhat loosely to an arm 47 on a shaft 48 mounted to turn in a bracket 49 on the sleeve 4 and in the bracket 9 (Fig. 1) of the casing 8. On the end of the shaft 48 remote from the bracket 49 there is a cam finger 50. A coiled spring 51, about the shaft 48 (Fig. 4) tends to rotate the shaft and swing the cam finger 50 inwardly, that is, to the left in Fig. 1, the spring 51 being secured at one end to the bracket 9, the opposite end of the spring being secured at 52 to the shaft 48.

The cam finger 50 is adapted to be actuated, and the shaft 48 is rotated, by a plunger 53 slideable in an inwardly projecting tubular guide 54 on the handle 11. In addition to serving as a means for actuating the cam finger 50 and rotating the shaft 48, the plunger 53 serves also as a means for holding the handle 11 in adjusted positions, since the inner end of the plunger is adapted to cooperate with a ratchet 55 on one end of the casing 8. The plunger 53 is moved inwardly by means of a short lever 56, shown in Fig. 4, the lever 56 being fulcrumed on the handle 11 and being actuated, to slide the plunger 53 inwardly, by a spring 57 interposed between the lever and the handle 11.

A first vertically movable slide rod 58 is mounted for reciprocation in the lower arm 7 of the support 1 and is held in a portion of the table or bottle support 15, for vertical adjustment, by a set screw 59 shown in Fig. 1. The slide rod 58 is alined axially with the stem 31 of the valve 29 (Fig. 3), or when the table and bottle support 15 is raised, the slide rod will engage the stem 31 of the valve 29 and open the valve.

Hangers 65 (Fig. 1) are secured to opposite sides of the upper arm 6 and in the hangers are journaled upper feed rollers 66 and 67, and lower feed rollers 68 and 69, the feed roller 68 coop-

erating with the feed roller 66, and the feed roller 69 cooperating with the feed roller 67. The roll 119 of material out of which the bottle cap is to be cut, is mounted on a platform 118 carried by the hangers 65, the roll being supported 5 behind a stop 117, mounted at 116 on the platform 118 for adjustment therewith. From the platform 118, the capping material passes between the feed rolls 66-68 and 67-69.

The feed rollers 66 and 68 are connected by intermeshing gears 71 (Fig. 2). The feed rollers 67 and 69 are connected by corresponding intermeshing gears 70 (Fig. 9). The shafts of the rollers 68 and 69 are connected by a chain and sprocket gearing 72 (Figs. 9 and 2). A pinion 15 73 on the shaft of the roller 68 meshes with a gear wheel 74 rotatable on the shaft of the roller 66. A back stop pawl 75, pivotally mounted on one of the hangers 65, cooperates with the gear wheel 74. A crank disk 76 is rotatable on the shaft of the roll 66 and is connected to the gear wheel 74 by a one-way clutch mechanism 77. A head H (Fig. 8) on the shaft of the roll 66 holds the disk 76 on the said shaft for rotation, the disk having a groove G for lubricant, disposed behind the disk. A sleeve guide 78 is pivoted to the crank disk 76, eccentrically thereof. A connecting rod 79 is slideable longitudinally in the guide 78 within a guard 100 on the arm 6. The connecting rod 79 is equipped with adjustable 30 abutments 80, located above and below the sleeve guide 78, and the abutments 80 may be located in various positions longitudinally of the connecting rod 79. The connecting rod 79 is made in two parts and on the inner ends of its parts a sleeve 81 is oppositely threaded to vary the length of the connecting rod 79. The lower end of the connecting rod 79 is pivoted at 82 to a crank arm 83 mounted to swing on a shaft 84 which is journaled in outstanding bearing projections 85 40 on the lower arm 7 of the support 1. Located alongside the crank arm 83 is another crank arm 86 which is secured to the shaft 84. The crank arm 83 has an arcuate slot 87, and the crank arm 86 has a projection or bolt 88 movable in the slot 87. The shaft 84 is connected to the shaft 10 by intermeshing beveled gears 89.

A slide rod 90 is mounted for vertical reciprocation in the arms 6 and 7 of the support 1. An angular bracket 91 is adjustable along the slide rod 90, and is held in adjusted positions by a clamp screw 92. The bracket 91 (Fig. 5) is adapted to rest on the arm 7 of the support 1. A stop screw 93 serves as a means for regulating the position of the bracket 91 on the slide rod 90, and is threaded into a block 94, secured at 95 to the slide rod 90. An adjustable shoulder lever 96 is fulcrumed intermediate its ends, at 97, on the bracket 91. The shoulder lever 96 is supplied with a lower inclined surface 98. The position of the shoulder lever 96 is adjusted by means of a screw 150, threaded into the shoulder lever and engaging the block 91. The screw 150 is kept in engagement with the block 91 by a spring 120, held between the lower end of the lever and the block 91.

The surface 98 of the shoulder lever 96 is adapted to cooperate with an eccentric pin 99, secured between disks 101 on the shaft 84. To the upper end of the slide rod 90 is attached a 70 cutter carrier 102 having an opening 103, the cutter-carrier being provided with an annular blade 104. The blade 104 is mounted for reciprocation in a guide plate 105. The guide plate 105 is mounted slidably, on studs 106 carried by a stop 75

plate 107 having an opening 108. On the lower surface of the stop plate 107 there is a soft facing 109, preferably made of copper, and the blade 104 can cooperate with the facing 109, without damage to the blade. The cutter carrier 102 has a limited upward and downward movement on the studs 106. Compression springs 110 are carried by the studs 106, and are interposed between the guide plate 105 and the facing 109 on the stop plate 107. Compression springs 111 (Fig. 1) are carried by the studs 106, and are located between the guide plate 105 and the cutter carrier 102.

The position of the stop plate 107, and associated parts, is limited by adjusting screws 112, threaded into lugs 113 on the head 17, and held in adjusted positions by lock nuts 114.

By means of the handle 11, the shaft 10 is rocked, and the pinion 12, meshing with the rack bar 14, raises the bottle support or table 15. As the bottle is raised, and assuming for the time being that a cap disk has been cut from the material 118, the top of the bottle picks up the disk and carries it upwardly. The boss 63 on the diaphragm 62 presses down the capping disk upon the ordinary pasteboard closure in the neck of the milk bottle. As the diaphragm 62 is carried upwardly, the bottle is centered by the rib 64. The rib 64 acts as a reinforcement for the cup-shaped member 60 and prevents irregular stretching or distortion of the diaphragm 62, the rib turning or rolling on its central axis 200, as the diaphragm 62 rises. The result is that the cap is applied smoothly and evenly over the neck of the bottle. As the diaphragm 62 moves upwardly, it engages the rubber cushion 22 and additional pressure is supplied, to keep the cap on the bottle. When the diaphragm 62 is carried upwardly, it closes the bore 23 in the cushion 22 and, therefore, closes the vent line 19.

40 As the table or bottle support 15 moves upwardly, the slide rod 58 is raised. The slide rod 58, cooperating with the valve stem 31 of Fig. 3, raises the valve 29 and opens it. Now there is established an air line including the pipe 27, the
45 space shown at 33 in Fig. 3, the duct 34 of Fig. 9 and the pressure space 25 about the sleeve 21. The diaphragm 62 is carried downwardly around the top of the neck of the bottle, and the bottle cap is pressed tightly around the bottle neck.
50 The air under pressure is heated by the means indicated at 26.

When the operator wishes to exhaust the air under pressure from the space shown at 25, he tilts the lever 56 of Fig. 4 on the handle 11, and the plunger 53 is carried outwardly until it is in the path of the cam finger 50 (Fig. 1) on the shaft 48. The shaft 48 is rotated, and the arm 47 on the shaft cooperates with stem 41, to raise the valve 40 of Fig. 3, and open it. Under such circumstances, an exhaust from the air space 25 of Figs. 9 and 6 is had, through the duct 35, the pipe 36, the valve casing 37 of Fig. 3, and the outlet pipe 39.

When the shaft 10 is rotated by the handle 11, the intermeshing gears 89 of Fig. 4 rotate the shaft 84, the eccentric pin 99 of Fig. 5 cooperates with the inclined surface 98 of the shoulder lever 96, the slide rod 90 is raised, and the blade 104 of Fig. 6 cuts the capping disk out of the material shown at 118. Ultimately, the eccentric pin 99 of Fig. 5 rides clear of the inclined surface 98 of the shoulder lever 96, and the slide rod 90 moves downwardly, carrying with it, to the position of Fig. 6, the cutting blade 104.

75 At an appropriate time in its upward move-

ment, the crank arm 86 on the shaft 84, being provided with the projection 88, picks up the crank arm 83 and raises it, motion being transmitted by the connecting rod 79 and the appropriate one of the abutments 80 to the crank disk 76, by way of the guide sleeve 78, the clutch mechanism 77 imparting rotation to the shaft of the roller 68 by way of the gears 74 and 73, and rotation being imparted to the shaft of the roller 66 by way of the gears 71, motion being transmitted to the shaft of the roll 69 by way of the chain and sprocket mechanism 72, and motion being transmitted from the shaft of the roll 69 to the shaft of the roll 67 by the gearing shown at 70. When the rollers 66-68 and 67-69 are actuated, the material 118 is advanced, so that a disk can be severed from it by the cutter 104. The arcuate slot 87 in the crank arm 83 of Fig. 1, receiving the projection 88 on the crank arm 86, permits the crank arm 83, which is mounted to swing on the shaft 84 to return to the position of Fig. 1, independently of the crank arm 86.

The function of the vent passage 23-19 of Fig. 6 is to prevent an air seal adhesion between the diaphragm 62 and the cushion 22, the diaphragm thus being enabled to clear itself readily from the cushion 22.

The strip 119 is not fed whilst the strip is gripped by the cutter 104 and there is no buckling of the strip. The avoiding of this undesirable condition is solely a matter of timing and the mechanism of Fig. 5 provides for a proper timing. By means of the screw 150, the lever 96 can be so positioned that the crank pin 99 will be in contact with the inclined surface 98 of the lever 96 at the proper time to actuate the slide rod 90 and the cutter 104 whilst the strip-feed is not at work. On the working stroke of the connecting rod 79, the one-way clutch 77 is operative, but on the return stroke of the connecting rod 79, the one-way clutch is inoperative. The slot 87 of Fig. 1 in the arm 83 permits the connecting rod 79 and the arm 83 to make the return stroke.

The machine forming the subject matter of this application presents many improvements over Patent 2,110,898, issued to George B. West on March 18, 1938, whereof I am the assignee. 45

What is claimed is:

What is claimed is:

1. In a receptacle-capping machine, a tubular head, a resilient cap-applying diaphragm extended transversely of the head and provided with an annular bead limiting and regulating the stretching of the bead when the diaphragm is engaged across the mouth of a receptacle, means for moving a receptacle until the diaphragm is engaged across the mouth thereof, and means for admitting fluid pressure to the head to flex the diaphragm lengthwise of the receptacle and about the neck thereof, to apply a cap thereto.

2. In a receptacle-capping machine, a tubular head, a resilient cap-applying diaphragm extended transversely of the head and provided with an annular bead limiting and regulating the stretching of the bead when the diaphragm is engaged across the mouth of a receptacle, the diaphragm having an external boss constituting means for seating a cap in the mouth of a receptacle and on a closure disk in the mouth of a receptacle, means for moving a receptacle until the diaphragm is engaged across the mouth thereof, and means for admitting fluid pressure to the head to flex the diaphragm lengthwise of

the receptacle and about the neck thereof, to apply a cap thereto.

3. In a receptacle-capping machine, a cap-
5 applying head, operable by fluid pressure, means
for conducting fluid pressure to the head, a re-
ceptacle carrier movable toward and from the
head, an exhaust conduit leading from the head,
10 a first mechanism for opening and closing the
exhaust conduit, and a second mechanism for
moving the carrier toward and away from the
head, said mechanisms each including an actuating
handle part, and said actuating handle
15 parts being located so closely together, and having
such movement relatively to each other, that
they can be grasped simultaneously by one hand
of an operator, the actuating handle part for the
first mechanism being movable with the actuating
20 handle part for the second mechanism, but in
inoperative position, during the entire stroke of
the actuating handle part for the second mech-
anism, and being capable of independent actua-
tion at the will of an operator.

4. In a receptacle-capping machine, a support,
25 a cap-applying means on the support, a cap-
cutter movable on the support, toward and away
from the cap-applying means, means for feed-
ing a strip of cap material between the cutter
and the cap-applying means, a receptacle car-
30 rier movable on the support, toward and away
from the cap-applying means and the cutter,
means for moving the carrier as aforesaid, the
last-specified means including a shaft journaled
35 on the support and having an eccentric, means
for operating the cutter, and including a slide
mounted to reciprocate on the support, a mem-
ber having a shoulder to be engaged by the ec-
centric, and means for mounting said member on
40 the slide, for adjustment toward and away from
the eccentric.

5. In a receptacle-capping machine, a support,
45 a cap-applying means on the support, a cap-
cutter movable on the support, toward and away
from the cap-applying means, means for feed-
ing a strip of cap material between the cutter and
the cap-applying means, a receptacle carrier
50 movable on the support, toward and away from
the cap-applying means and the cutter, means
for moving the carrier as aforesaid, the last-

specified means including a shaft journaled on
the support and having an eccentric, means for
operating the cutter and including a slide
5 mounted to reciprocate on the support, a mem-
ber having a shoulder to be engaged by the
eccentric, and means for mounting said member
on the slide, for adjustment longitudinally of
the slide and transversely of the eccentric.

6. A receptacle-capping machine constructed
as set forth in claim 4, and wherein said member
10 is a lever fulcrumed on a part of the last-specified
means, and an adjusting device coacting
with the lever and said last-specified means, to
tilt the lever and adjust the shoulder transversely
15 of the eccentric.

7. In a receptacle-capping machine, a support,
20 a cap-applying means on the support, a cap cutter
movable on the support, toward and away
from the cap-applying means, means for feeding
a strip of cap material between the cutter and
the cap-applying means, a receptacle carrier
25 movable on the support, toward and away from
the cap-applying means and the cutter, means
for moving the carrier as aforesaid, the last-
specified means including a shaft journaled on
30 the support and having an eccentric, means for
operating the cutter and including a slide
mounted to reciprocate on the support, a bracket
adapted to come to rest on a part of the support,
means for securing the bracket to the slide for
35 adjustment longitudinally of the slide, a lever
fulcrumed intermediate its ends on the bracket
and provided at one end with a shoulder for en-
gagement with the eccentric, and means asso-
ciated with the opposite end of the lever and with
40 the bracket for tilting the lever and adjusting
the shoulder transversely of the eccentric.

8. A receptacle-capping machine constructed
as set forth in claim 1, in combination with a
45 resilient cushion in the head, and forming an
abutment for the diaphragm when the diaphragm
is engaged across the mouth of a receptacle, and
means for admitting air between the diaphragm
and the cushion, whilst the diaphragm is in
50 abutment with the cushion, thereby to prevent
surface adhesion between the diaphragm and the
cushion.

GEORGE E. WEST.
